N. S. Vedder, of Troy N. Y.
Assignor to
North. Chase & North, of Philadelphia, Pa.
Letters Patent No. 1312. Dated Sept. 4. 1860.

The schedule referred to in these Letters Patent and making part of the same.

To all whom it may concern:

Be it known that I, N. S. Vedder, of the City of Troy,
County of Rensselaer, and State of New York, have invented or produced a new
and original design for Stoves, and I do hereby declare that the following is a full
and exact description of the same, reference being had to the accompanying draw-
ings, in which-

Fig: 1 represents a perspective view of a top plate.

Fig: 2 - A perspective view of an ash pit.

Fig: 3 - a fire door.

Fig: 4 - An oven door.

a. b. c. d. e. f. represent mouldings and ornaments.

What I claim as my invention and desire to secure by
Letters Patent, is the design and configuration of the mouldings and ornaments,
as herein described, forming an ornamental design for stoves.
